UNITED STATES PATENT OFFICE.

JAMES M. SMITH, OF PHILADELPHIA, PENNSYLVANIA, ASSIGNOR OF ONE-THIRD TO CLARENCE L. ALTEMUS AND ONE-THIRD TO HERBERT B. BOWLES, BOTH OF PHILADELPHIA, PENNSYLVANIA.

SPARKING IGNITER.

No. 861,615.

Specification of Letters Patent.

Patented July 30, 1907.

Application filed February 3, 1905. Serial No. 243,968.

To all whom it may concern:

Be it known that I, JAMES M. SMITH, a citizen of the United States, residing at Philadelphia, in the county of Philadelphia and State of Pennsylvania, have invented certain new and useful Improvements in Sparking Igniters; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My present invention has reference to improvements in explosive gas engines; and, the invention has for its principal object the provision of engines of this class with a novel construction of electrical appliance or device for igniting the charges of explosive medium.

With this object in view, my invention consists, primarily, in the novel arrangement and construction of a circuit-closing or contact-making and breaking device which is to be used in connection with an induction coil, the primary coil of which is supplied from a storage battery or other source of electrical energy, and the secondary coil of the induction coil being connected in circuit with the spark or igniting device in the combustion chamber of the engine.

A further object of this invention is to provide a novel contact making and breaking device of the character hereinafter more fully set forth, the casing of which, and in consequence the operating parts of the device, can be adjusted in different positions against the side of the motor-casing, or other part thereof, so as to provide a means by which the time of closing the primary circuit may be varied to produce an earlier 35. or a later spark with reference to the stroke of the piston.

The invention is clearly illustrated in the accompanying drawings, in which:

Figure 1 is a general view of one form of explosive gas engine, parts of which are represented in elevation and other parts thereof being shown in section, with a sectional view of the contact making and breaking device, embodying the principles of this invention, in position and connected in circuit with a source of electricity and an induction coil, said view also illustrating the manner of connecting in circuit the said induction coil with the igniting device of the gas engine. Fig. 2 is a vertical section of the several parts illustrated in said Fig. 1, the said section being taken on line 2—2 in said figure. Fig. 3 is a view, on an enlarged scale, of the contact-making and breaking device, the casing of the same being represented in vertical section, and the operating mechanism or working parts thereof being shown in elevation; Fig. 4 is a vertical cross section of the said contact-making and breaking device, said section being taken on line 4—4 in said Fig. 3; and Fig. 5 is a vertical section of the device, taken on line 5—5 in said Fig. 4. Figs. 6 and 7 are a top and bottom view, respectively, of the contact-making parts of the said device, detached from the casing. Fig. 8 is a longitudinal vertical section of the igniting device, employed in connection with the combustion chamber of the engine.

Similar characters of reference are employed in all of the said above described views, to indicate corresponding parts.

Referring now to the said drawings, the reference character 1 indicates the cylinder of any one of the usual forms of explosive gas engines, the upper portion thereof, in Figs. 1 and 2 of the drawings, being represented in vertical section to clearly illustrate the arrangement of the combustion chamber 2 of said cylinder. The usual form of piston is indicated by the reference character 3, and 4 is the piston rod which is connected with the crank-disks 5. These crank disks are secured, in any well known manner, upon the respective portions 6 and 6' of the main shaft of the engine. The said portions 6 and 6', as will be seen from Fig. 2, rotate in suitable bearings in the crank-chamber 7 of the engine, and suitably secured upon the reduced end-portion of the shaft-portion 6' is a pinion 8. This pinion 8 is arranged and rotates in a chamber formed by a casing 9 which is secured against the side of the said crank-chamber 7 by means of bolts or pins 10. At any desired point is placed an induction coil 11, the primary coil of which has its binding posts 12 and 13 connected in circuit by means of the wires 14 and 15 with an electric battery 16, or other source of electrical energy, and also with the contact-making and breaking device, to be hereinafter more fully described. The terminals of the secondary coil of the induction coil 11 are indicated by the reference numerals 17 and 18, said post 17 being electrically connected with a suitable portion of the frame of the engine by means of the wire 19, while the other binding post 18 is electrically connected by means of the wire 20 with the spark or igniting device of the engine. The said spark or igniting device, which is more clearly illustrated in Fig. 8 of the drawings, consists, essentially, of a metallic bushing 21 which is provided with a shoulder 22 and a screw-portion 23 by means of which it is screwed in position in the combustion chamber 2 of the engine, as clearly illustrated in Fig. 1. Within the tubular portion of said bushing 21 is arranged a tubular stem 24 which is made of fiber or any other suitable insulating material. The said stem 24 is preferably provided with a shoulder 25 which is fitted in the enlarged portion 26 of the bushing 21 and rests against a shoulder 26' in the enlarged part 26, substantially as shown in said Fig. 8, being held in place by means of a suitable stuffing box 27 and the packing 28.

Within the tubular part or duct of the stem 24 is a metallic rod 29 which is provided with an enlargement 32 at its inner end, within the combustion chamber 2, and is provided upon its opposite and screw-threaded end 30 with a pair of screw-washers or nuts 31 between which I have secured the end of the wire 20 which is connected with the binding post 18 of the secondary coil of the induction coil 11, as clearly illustrated in Fig. 1 of the drawings. Thus, it will be evident, that when 10 the secondary coil of the induction coil 11 is excited, in the manner to be hereinafter more fully described, a complete electric circuit is established through the wire 19 and the engine, and through the wire 20 with the conductor rod 29, to an interval between the 15 enlargement 32 of said rod 29 and a bent contact-piece or wire 33 of the bushing 21 within the combustion chamber 2 of the engine. The interval of separation between the enlargement 32 and the piece or wire 33 is such that the high tension current will 20 readily jump from one of said parts to the other, thereby producing a spark which will ignite the gas or gaseous mixture to produce an explosion which drives the engine.

Having thus described the general arrangement of 25 the sparker or igniting device, and the manner of completing the electric circuit therethrough, I will now set forth the general arrangement and construction of the make and break device, its operation, and the manner of electrically connecting it with the battery 30 and the primary coil of the induction coil 11. As will be seen from an inspection of the several figures of the drawings, the said device consists, essentially, of a back-plate 34 and a flanged cover 35, both of which are suitably secured together by means of tie-bolts or pins 35 36 and 37, so as to form a casing. The said back-plate is preferably provided with curved slots 38 by means of which it can be adjustably secured against the face of the casing 9, by means of screws or bolts 39 and washers 40, as represented in Fig. 1. Suitably secured to the 40 frame of the crank-chamber 7 is a pin 41, upon which is rotatively arranged and held in position by means of a nut 43, a steep 42 which is provided with a projection or cam 44 for raising the exhaust valve 45 of the engine. In order that the said rotary sleeve may 45 receive its rotary motion, a gear 46 is secured thereon, said gear being in mesh with the pinion 8 upon the end of the portion 6' of the main driving shaft of the engine. The one end of the said sleeve 42 extends through an opening in the back-plate 34 into the interior of 50 the casing formed by said back-plate and its flanged cover 35, and has secured thereon, by means of a set-screw 47, or in any other manner, a ring 48 which is formed with a radially extending projection or actuating teat 48'. Within the said casing and secured against the back-plate 34 of the same, by means of the bolt 36, and by means of other screws 49 and 49', is a block 50 which is made from fiber or any other suitable insulating material. The said block 50 is provided with a vertical duct 51 in which I have secured a short metallic tube 52, the said tube being provided with an internal shoulder 53 and an internal screw-thread 54. In said screw-portion of the said tube 52 is a nut 55 in which is loosely arranged the screw-threaded shank 58 of a contact-plunger 57, and encircling the shank of 55 said plunger, between its lower squared portion and the under side of the said nut 55, is a spring 59, the tension of which can be varied by means of an adjusting nut 56, whereby the contact end of the plunger is made to extend farther down toward the ring 48, or farther away from the same, as may be necessary under 70 varying conditions, and whereby sliding contact between the projection or teat 48' and the contact end of the plunger 57 is made with greater or less ease and freedom, as may be required. The said block 50 is also provided in a portion 50' which extends from an 75 opening in the side of the flanged cover 35. This portion is provided with a laterally extending duct 60 in which I have arranged a binding post 61 which is provided with a binding screw 62, and has a screw-threaded end-portion 63 screwed into the side of the tube 52, so 80 as to establish an electrical connection therewith when the end of the circuit wire 14 is attached to the said binding post 61 and secured in place by means of the screw 62. In like manner, the said portion 50' of the block 50 is provided with a second laterally extending duct 64, in which I have arranged a binding post 65 which is provided with a binding screw 66 for securing the wire 15 to said post 65. The said binding post 65, as will be clearly seen from Fig. 5, is entirely insulated from the tube 52, and an electrical connection 90 is established between the inner end-portion of said binding post 65 and the back-plate 34, by means of the screw or bolt 49', as will be clearly evident. The arrangement and construction of these several parts is such, that as long as the projection or teat 48' of the 95 ring 48 is not in sliding engagement, or rather disconnected with the lower contact end of the plunger 57, no electric circuit will be completed through the primary coil of the induction coil 11, as will be well understood; but, when the said projection or teat 48' 100 is brought against the lower end of and in sliding engagement with the spring-actuated contact plunger 57, then a complete electric circuit will be established through the said primary coil, which induces the secondary coil to become energized with a high-tension 105 current, and produces a spark in the igniting device, in the manner previously described. During each revolution of the radially extending projection or teat 48', and at the time that the said primary coil becomes energized, the path of the current from the secondary 110 coil of the induction coil 11 is through the wire 20, through the parts of the sparker, shown in Fig. 8, through the frame-work of the engine, and finally through the wire 19 from the engine back to said secondary coil, as will be clearly evident from an inspection 115 of Fig. 1 of the drawings. As soon as the projection or teat 48' has passed beyond the contact end of the plunger 57, the electric circuit is again broken, and it will thus be seen that the current is only used during the time of explosion.

The arrangement of the curved slots 38 in the back-plate 34 of the make and break device is for the purpose of adjusting the said device, to the right or left on the spindle 41, and thereby bringing the end of the contact-plunger 57 farther away or closer to the projection 125 48' of the ring 48, which ring is always in a fixed position upon the said spindle 41. A practical means is thereby provided by which the time of closing the primary circuit may be varied so as to produce an earlier or later spark with reference to the stroke of 130

the piston of the engine, and whereby the speed of the engine can be varied.

I claim

1. In an explosive gas engine, the combination, with the frame of the engine, and a sparking or igniting device connected with said engine, of a contact making and breaking device consisting essentially, of a casing also secured to the frame of the engine, said casing being provided with an opening in its side, a rotary contact-making ring in said casing, a radially extending projection or teat on said ring, a block of insulating material in said casing said block having a portion extending from the opening in the side of said casing, a movable spring-actuated contact-plunger in said block, said plunger having its one end normally extending into the path of the rotary movement of said projection or teat so as to make electrical contact, and a pair of terminals in that part of the block which extends from the casing, one of said terminals being insulated from said plunger, and the other terminal being electrically connected with said plunger, and an induction coil having a primary coil in circuit with the two terminals of said block, and having a secondary coil in circuit with the said sparking or igniting device, substantially as and for the purposes set forth.
2. In an explosive gas engine, the combination, with the engine, of an electric contact making and breaking device, consisting, essentially, of a casing, said casing being provided with an opening in its side, a block of insulating material in said casing, said block being provided with a vertical duct, and a pair of laterally extending ducts in that part of the block which extends from the casing, a contact-plunger movably arranged in said vertical duct, and an electric terminal in each lateral duct, the terminal in one of said lateral ducts being insulated from said plunger, but the other terminal in the other lateral duct making electrical contact with said plunger, and a plunger-engaging means provided with a radially extending contacting teat or projection, substantially as and for the purposes set forth.
3. In an explosive gas engine, the combination, with the engine, of an electric contact making and breaking device, consisting, essentially, of a casing, said casing being provided with an opening in its side, a block of insulating material in said casing, said block being provided with a vertical duct, and a pair of laterally extending ducts in that part of the block which extends from the casing, a metallic tubing in said vertical duct, a contact-plunger movably arranged in said metallic tubing, and an electric terminal in each lateral duct, the terminal in one of said lateral ducts being insulated from said metallic tubing, and an end-portion of the said other terminal in the other lateral duct being connected with said metallic tubing and making electrical contact therewith, substantially as and for the purposes set forth.
4. In an explosive gas engine, the combination, with the engine and its shaft, of an electric contact making and breaking device, consisting, essentially, of a casing, said casing being provided with an opening in its side, a block of insulating material in said casing, said block being provided with a vertical duct, and a pair of laterally extending ducts in that part of the block which extends from the casing, a metallic tubing in said vertical duct provided with an internal screw-portion at its upper end, a nut screwed into said screw-portion of said metallic tubing, a contact-plunger movably arranged in said tubing having a lower squared end-portion and a screw-threaded shank extending through said nut, a spring encircling said shank between said squared end-portion of the plunger and said nut, an adjusting nut upon the upper portion of said screw-threaded shank, a ring secured upon the shaft of the engine, and a projection extending from said ring adapted to be brought in engagement with the end-portion of said plunger, and an electrical terminal in each lateral duct, the terminal in one of said lateral ducts being insulated from said metallic tubing, and an end-portion of the said other terminal in the other lateral duct being connected with said metallic tubing and making electrical contact therewith, substantially as and for the purposes set forth.
5. In an explosive gas engine, the combination, with the engine and its shaft, of an electric contact making and breaking device, consisting, essentially, of a casing, said casing being provided with an opening in its side, a block of insulating material in said casing, said block being provided with a vertical duct, and a pair of laterally extending ducts in that part of the block which extends from the casing, a metallic tubing in said vertical duct provided with an internal screw-portion at its upper end, a nut screwed into said screw-portion of said metallic tubing, a contact-plunger movably arranged in said tubing having a lower squared end-portion, a screw-threaded shank between said squared end-portion of the plunger and the said nut, an adjusting nut on the upper portion of said screw-threaded shank, a ring secured upon the shaft of the engine, and a projection extending from said ring adapted to be brought in engagement with the end-portion of said plunger, and an electrical terminal in each lateral duct.
6. In an explosive gas engine, the combination, with the frame of the engine and its shaft, of an electric contact making and breaking device, comprising a casing, consisting, essentially, of a back-plate having slotted portions, and a flanged cover, means in said slotted portions of the back-plate for adjustably securing said casing to the frame of the engine, said casing being provided with an opening in its side, a block of insulating material in said casing, said block being provided with a vertical duct, and a pair of laterally extending ducts in that part of the block which extends from the casing, a contact-plunger movably arranged in said vertical duct, a ring secured upon the shaft of the engine, and a projection extending from said ring adapted to be brought in engagement with the end-portion of said plunger, an electric terminal 65 in one of said lateral ducts, insulated from said metallic tubing, but having a hole through which said screw or bolt 49 is passed and makes contact with said terminal 65, and a terminal 61 in the other lateral duct having an end-portion connected with said metallic tubing and making electrical contact with said metallic tubing, substantially as and for the purposes set forth.
7. In an explosive gas engine, the combination, with the frame of the engine and its shaft, of an electric contact making and breaking device, comprising a casing, consisting, essentially, of a back-plate having slotted portions, and a flanged cover, means in said slotted portions of the back-plate for adjustably securing said casing to the frame of the engine, said casing being provided with an opening in its side, a block of insulating material in said casing, said block being provided with a vertical duct, and a pair of laterally extending ducts in that part of the block which extends from the casing, a contact-plunger movably arranged in said vertical duct, a ring secured upon the shaft of the engine, and a projection extending from said ring adapted to be brought in engagement with the end-portion of said plunger, and an electrical terminal in each lateral duct, the terminal in one of said lateral ducts being insulated from said plunger, but the other terminal in the other lateral duct making electrical contact with said plunger, substantially as and for the purposes set forth.
8. In an explosive gas engine, the combination, with the frame of the engine and its shaft, of an electric contact making and breaking device, comprising a casing, consisting, essentially, of a back-plate having slotted portions, and a flanged cover, means in said slotted portions of the back-plate for adjustably securing said casing to the frame of the engine, said casing having an opening in its side, a block of insulating material in said casing, said block being provided with a vertical duct, and a pair of laterally extending ducts in that part of the block which extends from the casing, a metallic tubing in said vertical duct, a contact-plunger movably arranged in said metallic tubing, a ring secured upon the shaft of the engine, and a projection extending from said ring adapted to be brought in engagement with the end-portion of said plunger, and an electric terminal in each lateral duct, the terminal in one of said lateral ducts being insulated from said metallic tubing, and an end-portion of the other terminal in the other lateral duct being connected with said metallic tubing and making electrical contact therewith, substantially as and for the purposes set forth.
9. In an explosive gas engine, the combination, with the frame of the engine and its shaft, of an electric contact making and breaking device, comprising a casing, consisting, essentially, of a back-plate having slotted portions, and a flanged cover, means in said slotted portions of the back-plate for adjustably securing said casing to the frame of the engine, said casing being provided with an opening in its side, a block of insulating material in said casing, said block being provided with a vertical duct, and a pair of laterally extending ducts in that part of the block which extends from the casing, a metallic tubing in said vertical duct provided with an internal screw-portion at its upper end, a nut screwed into said screw-portion of said metallic tubing, a contact-plunger movably arranged in said tubing having a lower squared end-portion and a screw-threaded shank extending through said nut, a spring encircling said shank between said squared end-portion of the plunger and said nut, an adjusting nut on the upper portion of said screw-threaded shank, a ring secured upon the shaft of the engine, and a projection extending from said ring adapted to be brought in engagement with the end-portion of said plunger, and an electrical terminal in each lateral duct, the terminal in one of said lateral ducts being insulated from said metallic tubing, and an end-portion of the said other terminal in the other lateral duct being connected with said metallic tubing and making electrical contact therewith, substantially as and for the purposes set forth.

duct, the terminal in one of said lateral ducts being insulated from said metallic tubing, and an end-portion of the other terminal in the other lateral duct being connected with said metallic tubing and making electrical contact therewith, substantially as and for the purposes set forth.

9. In an explosive gas engine, the combination, with the frame of the engine and its shaft, of an electric contact making and breaking device, comprising a casing, consisting, essentially, of a back-plate having slotted portions, and a flanged cover, means in said slotted portions of the back-plate for adjustably securing said casing to the frame of the engine, said casing being provided with an opening in its side, a block of insulating material in said casing, 10 screws or bolts 49 and 49' for securing said block against said plate, said block being provided with a vertical duct, a ring secured upon the shaft of the engine, and a projection extending from said ring adapted to be brought in engagement with the end-portion of said plunger, and a

pair of laterally extending ducts in that part of the block 20 which extends from the casing, a metallic tubing in said vertical duct, a contact-plunger movably arranged in said metallic tubing, an electric terminal 65 in one of said lateral ducts, insulated from said metallic tubing, but having a hole through which said screw or bolt 49' is 25 passed and makes contact with the said terminal 65, and a terminal 61 in the other lateral duct having an end-portion connected with said metallic tubing and making electrical contact therewith, substantially as and for the purposes set forth.

15 In testimony, that I claim the invention set forth above I have hereunto set my hand this thirty first day of January, 1905.

JAMES M. SMITH.
